APPARATUS FOR CONTROLLING CENTRIFUGAL FORMATION OF SHEET MATERIAL

Robert S. Ames, Mauritz P. Peterson, and John C. Feldscher, Akron, Ohio, assignors to Good-year Aircraft Corporation, Akron, Ohio, a corporation of Delaware

Application June 14, 1946, Serial No. 676,694

9 Claims. (Cl. 18—19)

1

This invention relates to the centrifugal formation of shaped articles from plastic materials, especially to means for use in observing, determining and controlling the centrifugal formation of shaped articles from thermo-plastic sheet material.

The present invention relates to, and is especially suited for use with, the invention shown and described in an application of Robert Mayne, Serial No. 585,504, filed March 29, 1945, now Patent No. 2,448,492, and entitled "Methods and apparatus for centrifugally forming of sheet thermoplastics."

In the centrifugal formation of streamlined articles from sheets of thermo-plastic materials, the edges of the sheet of plastic, in pliable form, may be secured to a jig or fixture which in turn is mounted on a driven shaft in radially spaced relation thereto. Then, by the shaft's rotation, the sheet is gradually thrown or drawn out to form, at one stage, the desired article. Hence, the state of formation of the plastic sheet must be carefully observed, and this frequently is difficult since the plastic being formed may be transparent and it is, of course, being rotated rapidly about the shaft.

The general object of this invention is to provide an effective sighting device for use with apparatus for centrifugally forming sheet materials.

A further object of the invention is to provide a sturdy, non-breakable, inexpensive sighting arrangement for checking the centrifugal formation of large articles from plastic material.

Another object of the invention is to shield an operator's eyes substantially all of the time from the light which is associated with the forming apparatus and to permit only intermittent observation periods.

Another object of the invention is to provide artificial lighting for the article being formed which lighting is rotated with the article.

Another object of the invention is to employ a stroboscopic viewing device for observing the article being formed centrifugally.

The foregoing objects of the invention, and other objects which will be made apparent as the specification proceeds, are obtained by throwing a light on the sheet or article being formed and observing the light. The light may be carried to rotate with the article being formed, or if the light is stationary a sighting disc may be mounted to rotate with the shaft which carries the fixture or jig supporting the sheet or article to be formed.

2

For a better understanding of the invention, reference should be had to the accompanying drawings wherein:

Fig. 1 is a side elevation of one embodiment of apparatus, somewhat diagrammatically illustrated, incorporating the principles of the invention;

Fig. 2 is an end elevation of the apparatus of Fig. 1;

Fig. 3 is a view similar to Fig. 1 of another form of the invention; and

Fig. 4 is an end elevation of the apparatus of Fig. 3.

The form of the invention shown in Figs. 1 and 2 includes a base 1 which rotatably supports a shaft 2 adapted to be rotated at a selected or adjustable speed by any suitable means, for example, by way of a pulley 3. The shaft 2 adjustably carries radial arms 4 which support a jig or fixture 5 on which the thermo-plastic sheets to be formed are mounted, usually by clamping means which engage only the edges of the sheet after the sheet is draped in heated condition over or inside of the fixture, as disclosed, in part, in the said Mayne application above identified. Adjustable counterweights 6 are ordinarily provided on the ends of the arms 4 remote from the fixture 5.

A light source 7 is positioned on or adjacent the apparatus, and this is conveniently accomplished by providing an upstanding bar 8 at one end of the base which adjustably carries a bracket 9 on which the light 7 is mounted. Instead of being vertically directed the bar 8 may be horizontally or otherwise positioned to bring the light 7 nearer to the eye level of the average operator, especially for large work. Adjacent the other end of the base a rotatable sighting disc 11 is provided which is mounted on the shaft 2 for rotation therewith. The disc 11, as best seen in Fig. 2, is provided with an aperture 12, and across the aperture is adjustably mounted a sighting rod 13. The adjustment of the rod 13 may be achieved by providing a pair of slots 14 which slidably receive clamp bolts 16 which carry the ends of the rod.

In operation, the sheet S in heated condition is mounted on the jig or fixture 5 and the shaft 2 is set to rotating. The operator stands so that his eye E will line up the light 7 and the rod 13, specifically on line 17. He will also see the reflection of the light 7 off the surface of the sheet S on line 18. Thus the operator will periodically see the light 7 and its reflection as the aperture 12 in the sighting disc moves past his line of

vision. The effect is stroboscopic in that the light 7 comes into view only when the sheet S is in position to be viewed. The rotation of the shaft 2 at proper forming speed causes the sheet S to move outwardly during which time the light reflection point on the sheet as indicated by the line 18 moves outwardly within the vision of the operator until with the sheet S in fully formed or S¹ position the reflection and the direct line 17 merge at which time rotation of the shaft 2 is stopped or slowed to permit setting of the sheet without further forming.

Adjustment of the light source 7 and of the rod or of other parts of the apparatus can be made to effect the desired and controlled shaping of the sheet material.

Turning now to the form of the invention illustrated in Figs. 3 and 4, like numerals have been used for like parts except the suffix "a" has been added. The main feature of difference between this form of my invention and that previously described is that instead of holding the light stationary and using a sighting disc, the light source is rotated with the sheet S^a. The light source 7^a may be mounted on the jig 5^a, for example, at one end thereof. Another manner of mounting is to have the light 7^a carried adjustably, as by bracket 9^a, on a somewhat more rigid rod 8^a rotatably carried by the shaft 2^a. Electric current for lighting the light is supplied by slip rings 20 carried by the shaft 2^a.

A sighting rod 13^a is adjustably clamped by a bracket 16^a to a rod 21 mounted on one end of the base 1^a. The rod 21 may be extended horizontally or in other than a vertical position in order to bring the sighting rod 13^a closer to the eye level of the usual operator. Of course, if the rod 21 extends horizontally the rod 13^a will extend vertically. In this connection it may be noted that in one laboratory form of the apparatus a vertically extending string connected between ceiling and floor was used instead of the rods 21 and 13^a.

The operation of this form of the invention is very similar to that previously described. The eye E^a of the operator lines up the rod 13^a and the light 7^a on the line 17^a. At the same time a light reflection is seen on the line 18^a, and controlled rotation is continued until the reflection and the main light source verge together. Thereupon rotation is stopped or slowed to prevent further formative movement of the sheet and to insure setting of the sheet in the formed shape.

From the foregoing it will be evident that the objects of the invention have been achieved by the provision of comparatively simple and inexpensive, rugged, and easily operated apparatus for controlling the formation of thermo-plastic sheet materials.

Features of the several embodiments of the invention illustrated and described may be employed in forming "Plexiglas" and like sheet materials by non-rotative processes. Also, it is possible to combine parts of the inventive forms shown, for example, the sighting disc 11 of the invention of Figs. 1 and 2 may be included in the embodiment of the invention of Figs. 3 and 4, if desired, and if this is done either the rod 13 or rod 13^a will be omitted. Instead of employing the sighting disc 11 on the form of the invention of Figs. 3 and 4, a metal cover or shield may be used which surrounds the jig or fixture and which is mounted to travel therewith. Such a cover is spaced from the jig a sufficient distance to permit desired formation of the sheet, with the cover acting to protect the sheet against the air during

rotation and to prevent the sheet from ever flying out and hitting someone. A window or sighting aperture is provided in the cover.

Again, the rods 13 and 13^a may be made in the form of edge lighted strips of "Plexiglas" to increase their visibility. Furthermore, instead of using rods 13 and 13^a as sighting means the invention contemplates the use of cords or wires, and, also, the use of buttons or spot type sighting means.

Accordingly, even though the invention has been specifically illustrated and described, all in accord with the patent statutes, it should be specifically understood that the invention is not to be limited to the forms disclosed, but that the scope of the invention is defined in the appended claims.

What is claimed is:

1. Apparatus for forming thermo-plastic sheet material including a fixture for holding the heat softened sheet material adjacent its edge portions, a light source and a sighting means in alignment at periodic interval to define the outer boundary of the shaped sheet material, said light source being positioned to throw a reflection from the sheet material during shaping, and means for centrifugally shaping the sheet material until the reflection is brought into alignment with the light source and the sighting means.

2. Apparatus for forming thermo-plastic sheet material including a fixture for holding the heat softened sheet material adjacent its edge portions, an adjustable light source and an adjustable sighting means in alignment at periodic interval to define the outer boundary of the shaped sheet material, said light source and sighting means being relatively movable as the sheet is being formed, said light source being positioned to throw a reflection from the sheet material at intervals during shaping, and means for centrifugally shaping the sheet material until the reflection is brought into alignment with the light source and the sighting means.

3. Apparatus for forming a heat softened sheet including a jig for supporting edges of the sheet, means for rotatably supporting the jig, an adjustably positioned stationary light source, a sighting disc rotatable with the jig, said disc having a sighting aperture through which the operator can periodically, during the rotation of the disc, see the light source and the reflection of the light source on the sheet being formed, a sighting means adjustably carried in association with the aperture in the sighting disc, said sighting means and light source being aligned to define the line to which the sheet is to be shaped, and means to rotate the jig to centrifugally shape the sheet substantially until the reflection of the light source and the sighting means.

4. Apparatus for forming a heat softened sheet including a jig for supporting edges of the sheet, means for rotatably supporting the jig, a stationary light source, a sighting disc rotatable with the jig, said disc having a sighting aperture through which the operator can periodically, during the rotation of the disc, see the light source and the reflection of the light source on the sheet being formed, a sighting means carried in association with the aperture in the sighting disc, said sighting means and light source being aligned to define the line to which the sheet is to be shaped and means to rotate the jig to centrifugally shape the sheet substantially until the reflection of the

light source verges into the line between the light source and the sighting means.

5. Apparatus for forming a heat softened sheet including a jig for supporting edges of the sheet, means for rotatably supporting the jig, a radially adjustable light source mounted for rotation with the jig, said light source being adapted to throw a reflection on the sheet viewable to the operator, an adjustably mounted, stationary sighting means, the light source and the sighting means defining a line viewable to the operator's eye and marking the extent to which the sheet is to be shaped, and means for rotating the jig to centrifugally form the sheet substantially until the reflection of the light source verges into the line between the light source and the sighting means.

6. Apparatus for forming a heat softened sheet including a jig for supporting edges of the sheet, means for rotatably supporting the jig, a light source mounted for rotation with the jig, said light source being adapted to throw a reflection on the sheet viewable to the operator, a stationary sighting means, the light source and the sighting means defining a line viewable to the operator's eye and marking the extent to which the sheet is to be shaped, and means for rotating the jig to centrifugally form the sheet substantially until the reflection of the light source verges into the line between the light source and the sighting means.

7. In apparatus for centrifugally forming pliable sheet materials wherein a strong light is provided to aid in following formation of the article, a shaft, journal means for said shaft, means for rotating said shaft, a fixture adjustably secured to said shaft in axial alignment but radially spaced from said shaft, said fixture being adapted to have the sheet of material to be formed secured thereto so as to support the edges of same but leave the center portion free for forming movement, and a solid disc of appreciable size carried by said shaft adjacent one end thereof, said disc having a relatively small aperture

45

therein in horizontal and axial alignment with the radially outer section of said fixture whereby a machine operator can stand adjacent to said disc and be shielded from the glare on said apparatus substantially all of the time but can observe the stage of formation of the sheet on the fixture through the disc aperture when it is moved past his horizontal line of vision.

8. In apparatus for centrifugally forming transparent thermo-plastic materials, wherein a forming fixture mounted on a rotational support shaft is provided and a strong light is provided thereon, the combination with the rotational support shaft of a sighting disc, said disc being solid to shield the operator's eyes from the strong light of the apparatus and being provided with one aperture therein in horizontal and axial alignment with the forming fixture of the apparatus so that the operator can obtain an instantaneous sight of the fixture as the aperture in the disc is moved past his line of vision.

9. In centrifugal forming apparatus for thermo-plastic materials wherein a forming fixture and a rotational support therefor are provided, the combination with the rotational support of a sighting disc, said disc being opaque and being provided with one aperture therein in horizontal and axial alignment with the radially outer section of the forming fixture of the apparatus.

Certificate of Correction

Patent No. 2,454,116.

November 16, 1948.

ROBERT S. AMES ET AL.

It is hereby certified that error appears in the printed specification of the above numbered patent requiring correction as follows:

Column 5, line 7, strike out the words and syllable "radially adjustable light source mounted for rota-";

and that the said Letters Patent should be read with this correction therein that the same may conform to the record of the case in the Patent Office.

Signed and sealed this 29th day of March, A. D. 1949.
